US00D907652S

(12) **United States Design Patent** (10) Patent No.: **US D907,652 S**
Momchilov et al. (45) Date of Patent: **** Jan. 12, 2021**

(54) **DISPLAY SCREEN OR PORTION THEREOF WITH GRAPHICAL USER INTERFACE**

(71) Applicant: **Citrix Systems, Inc.**, Fort Lauderdale, FL (US)

(72) Inventors: **Georgy Momchilov**, Parkland, FL (US); **Chris Pavlou**, Boca Raton, FL (US)

(73) Assignee: **Citrix Systems, Inc.**, Fort Lauderdale, FL (US)

(**) Term: **15 Years**

(21) Appl. No.: **29/678,453**

(22) Filed: **Jan. 29, 2019**

Related U.S. Application Data

(63) Continuation of application No. 16/164,258, filed on Oct. 18, 2018, now Pat. No. 10,673,845, which is a continuation of application No. 15/150,558, filed on May 10, 2016, now Pat. No. 10,122,709.

(57) **CLAIM**

The ornamental design for a display screen or portion thereof with graphical user interface, as shown and described.

DESCRIPTION

FIG. 1 is a front view of a display screen or portion thereof with graphical user interface showing our new design; and, FIG. 2 is a front view of the design of FIG. 1 shown in an illustrative environment.

The broken lines depicting the illustrative environment show features that form no part of the claimed design.

1 Claim, 2 Drawing Sheets
